UNITED STATES PATENT OFFICE

JAMES BALTON, OF BALTIMORE, MARYLAND, ASSIGNOR TO JOSEPH SHAPIRO, OF BALTIMORE, MARYLAND

DESIGN FOR A FAUCET

Application filed May 12, 1933. Serial No. 48,093. Term of patent 7 years.

To all whom it may concern:

Be it known that I, JAMES BALTON, a citizen of the United States, residing at Baltimore, State of Maryland, have invented a new, original, and ornamental Design for Faucets, of which the following is a specification, reference being had to the accompanying drawing, forming a part thereof.

Figure 1 is a perspective view of a faucet, showing my new design.

Figure 2 is a top plan view.

Figure 3 is a side elevation.

Figure 4 is a front elevation.

I claim:

The ornamental design for a faucet substantially as shown.

JAMES BALTON.
